Mr. Walter Owen. Attn:

UNITED STATES PATENT OFFICE.

HANS SENGBUSCH, OF CHICAGO, ILLINOIS, ASSIGNOR TO AUTOMATIC ELECTRIC INC., OF CHICAGO, ILLINOIS, A CORPORATION OF DELAWARE.

HAND TELEPHONE.

Application filed May 29, 1924. Serial No. 716,576.

The present invention relates to hand telephones provided with impulse transmitters and adapted for use with automatic telephone systems. These hand telephones are particularly, although not exclusively, used by telephone repair men.

The general object of the invention is to provide a new and improved hand telephone which has the advantages, among others, of compactness, good balance, and simple construction. In addition, the parts of this hand telephone are very readily accessible for repair, and the whole make-up is exceedingly neat in appearance.

A particular feature of the invention is the construction of the shell in halves, making each half a simple casting which may be manufactured very cheaply.

Another advantage of casting the shell in halves is the convenience of accessibility, it being possible to assemble all parts and to even complete the wiring operation before fastening the two halves together.

The invention will be best understood from the following detailed description taken in connection with the accompanying drawings comprising Figs. 1 to 6, inclusive.

Fig. 1 is a front view of the hand telephone with part of the handle broken away; Fig. 2 is a side view of Fig. 1 as seen when looking in the direction indicated by arrows A—A; Fig. 3 is a side view of Fig. 2 as seen when looking in the direction indicated by arrows B—B; Fig. 4 is a cross-sectional view of the hand telephone as seen when looking in the direction indicated by arrows F—F in Fig. 1, the resistance coil, condenser, and a portion of the transmitter being shown in full and the terminal block 18' being shown in cross section when looking in the direction indicated by the arrows H—H, Fig. 6; Fig. 5 is a view of that half of the hand telephone at the left of the dotted line G—G as seen when looking in the direction indicated by arrows D—D, showing the transmitter complete and in place, and the push button switch, with its micarta cover 36 partly broken away; while Fig. 6 shows that part of the telephone lying to the right of line G—G as it appears when looking in the direction indicated by arrows E—E.

As above pointed out the housing or shell for supporting the various elements of the telephone is made up of two castings. As will be noted from Figs. 1, 2, 4, and 5 the

casting 1 consists of a channel member having a cup-like opening at one end in the form of a watch-case receiver shell, while the other end is in the form of a cup for receiving a telephone transmitter unit, such as the unit 3.

Hand telephones of this kind are usually provided with two button operated switches, one of which, when its button is depressed, short circuits a condenser located in the receiver and transmitter circuit, and the other, when depressed, opens a short circuit around a resistance located in the line circuit. These push button spring combinations in the present case are located in the channel connecting the above described cups and are mounted on a block fixed to the casting by the screw 30. The two buttons 9 and 10 for operating the push button switches are held in place by the pairs of springs 11 and 12 which they operate, as is clearly shown in Fig. 5. The location of these buttons is such that they may be conveniently operated one by the thumb and the other by the forefinger. These springs are provided with a micarta cover 36 which is held in place by screws 14.

The transmitter unit is held in place by two screws 4 and 4', respectively, which are provided with circular nuts 5 and 5' which are drilled and tapped on an eccentric so that when the screws are tightened up the nuts bear against the transmitter unit as illustrated in Figs. 4 and 5.

Casting 2, which is shown in Figs. 2, 3, 4, and 6, consists of a channel member provided at one end with two diametrically disposed winged extensions 31 and 32 which serve, when the two castings are assembled together, as a cover for the transmitter cup portion of casting 1. The other end of casting 2 is cup shaped for receiving a standard dial type calling device 33. The channel portion of this casting which extends from the cup shaped end to the other extreme end serves as a receptacle for the condenser 15, and the unit comprising distributing block 18, resistance winding 19, and terminal block 18' which are held in place by the screws 17 and 17' and fiber washers 16 and 16', respectively.

The two castings or halves of the hand telephone are not connected together until their associated parts are in place and all wiring between the two halves completed.

When this is done the two halves are placed together and held by screws 38, 38', 39, and 39', respectively.

The openings in the bottom end of the 5 terminal block 18' allow the line conductor terminals, such as 20, to be led in to the terminals on the inside of the instrument and the openings 50 (see Figs. 3 and 4) in the casting 2 permit the line terminals to be 10 fixed in place or removed without opening up the instrument.

It is of course understood that the hand telephone herein shown and described may be modified as regards its design and form 15 without departing from the spirit of the invention as defined in the claims.

What is claimed is:

1. In a hand telephone, two castings each provided with a plurality of cavities, a telephone receiver, a telephone transmitter, a 20 pair of push button switches in the cavities of one casting, an impulse transmitter, a condenser, a terminal block, and a resistance unit in the cavities of the other casting, and 25 means for fitting said castings together as a unit.

2. In a hand telephone, two castings each provided with a plurality of cavities, a telephone receiver, a telephone transmitter, a 30 pair of push button switches in the cavities of one casting, an impulse transmitter, a condenser, a terminal block, and a resistance unit in the cavities of the other casting, and means for fitting said castings together 35 as a unit so that the receiver and impulse transmitter are faced back to back and separated by one of said castings.

3. A hand telephone set comprising two 40 castings, one casting having cavities serving as housings for a receiver and a transmitter, respectively, said cavities being connected by a channel portion of said casting serving as

a housing for a pair of push button switches, the other casting having a portion for covering the back of the transmitter housing; 45 a ring member serving as a housing for a calling device, and a channel in said casting for receiving a condenser and an induction coil, and means for securing said castings together. 50

4. In a hand telephone set, a transmitter, a cavity for holding said transmitter, and means comprising screws and cooperating eccentric nuts for securing said transmitter in place. 55

5. A hand telephone comprising two major units, one unit comprising a shell, an impulse transmitter, a condenser, a resistance coil, and terminal blocks, the other unit comprising a shell, a receiver, a transmitter 60 and push button switches, and means for fastening said major units together as a whole.

6. A hand telephone comprising a casting provided with cavities for receiving transmitter and receiver units respectively, a threaded extension formed from a part of said casting with cooperating means for holding the receiver unit in place, eccentric devices for holding the transmitter in place 70 and perforations in said casting through which sound waves may pass to the transmitter unit. 75

7. In a hand telephone a voice current transmitter, a receiver and an impulse transmitter, a single receptacle for holding both the voice current transmitter and the receiver, and a second receptacle for completely inclosing the transmitter and for receiving the impulse transmitter. 80

In witness whereof, I hereunto subscribe my name this 22nd day of May, A. D., 1924.

HANS SENGBUSCH.
